PAPER CONTAINER

Harry Wootton, Upper Montclair, N. J., assignor to
Mono Service Co., Newark, N. J.

Application February 25, 1933, Serial No. 658,585

1 Claim. (Cl. 229—51)

This invention relates to paper containers such as are described in the applications already filed in the names of Elmer Zebley Taylor, Serial No. 570,427, dated October 22, 1931, Edmund Paul Herrmann, Serial No. 632,598, dated September 10, 1932, and Edmund Paul Herrmann, Serial No. 649,648, dated December 30, 1932, and comprising in each case a conical double-walled body in one end of which a closure is secured. After 10 filling a closure is to be applied to the other end, and special means are described in each of the said prior applications for subsequently opening the container, consisting in the formation of weakening lines around that part of the blank 15 which forms that end of the body at which the container is to be opened, so that the portion between such weakening lines can be torn out, thus separating the end of the body with the closure secured therein from the main body of the container and exposing the contents for use as required.

In the preferred form described in the prior applications above referred to the container is to be opened at the smaller end, but in the present 25 invention the container is to be opened at the larger end, and the construction is such that the removed end with the closure secured therein can be very conveniently used as a cover for the container if all the contents have not been removed. 30 The invention is illustrated in the accompanying drawing, in which Fig. 1 represents on an enlarged scale a portion of the upper end of a filled container; Fig. 2 shows the upper end of such container separated and in use as a cover; Fig. 3 shows a modified arrangement in which a different form of end closure is employed, and Figs. 4, 5 and 6 suitable arrangements of the weakening lines on the body blank.

In carrying out the present invention a blank 40 1 is employed for the conical body in which weakening lines 3, 4, are formed, which may be arranged as shown for example in either of the ways illustrated in Figs. 4, 5 and 6. In Fig. 4 it will be seen that, as described in Elmer Zebley 45 Taylor's prior application No. 570,427 above referred to, the line 3 extends parallel with the edge of the blank 1 throughout the whole length thereof, and that line 4 is also parallel with such edge in the part which forms the inner wall of the container and then widens out and extends spirally along the part constituting the outer wall, and that a tab 5 is left on the edge of the blank between the outer ends of the weakening 50 lines 3, 4. When this arrangement is employed it is necessary in tearing out the strip between

the weakening lines to open the container to make two complete turns around the latter, but if the arrangements of weakening lines shown in Figs. 5 and 6 are employed the entire strip 6 can be torn out by a single turn around the container. 5

In Fig. 5 the weakening lines 3, 4, are arranged as described in the specification of Edmund Paul Herrmann's prior United States application Serial No. 632,598, the line 3 being again parallel with the edge of blank 1 throughout its length, and line 4 also parallel therewith throughout its length but spaced farther away from line 3 in the portion forming the outer wall of the body of the container than in the portion forming the inner wall, and a cut 7 being made at a suitable point 10 between the weakening lines to form a tab by which both portions of the strip 6 can be torn out in one turn around the container. 15

Fig. 6 shows the arrangement described in Edmund Paul Herrmann's prior United States application Serial No. 649,648, in which line 3 is again parallel with the edge of blank 1, and line 4 also parallel therewith in the portion forming the inner wall, and then extending spirally around the part forming the outer wall, a tab 5 being left 20 on the edge of the blank as in the arrangement shown in Fig. 4. A cut 8 is made at a point which when the blank is rolled up to form the conical body of the container comes immediately beneath the tab 5, and the adhesive employed is in 25 this case applied to the part of the inner wall adjacent to this cut 8, so that when the tab is pulled to open the container the adhesion between the inner and outer parts of strip 6 will cause them both to be torn out at one operation, by a single 30 turn around the container. 35

When the arrangements shown in Figs. 4 and 5 are employed the strip 6 between the weakening lines 3, 4, may be left uncoated with adhesive, or only lightly coated, the adhesion caused by the 40 treatment with paraffin wax or other waterproofing agent being depended on either entirely or partially to hold the two walls of the body together at this point.

The blank 1, with weakening lines according to 45 these or other suitable arrangements, is rolled up to form a conical double-walled body 2, and a closure of suitable form is secured at its smaller end. The upper edge of the body is turned over outwardly as shown at 10 on the left hand side of 50 Fig. 1, and a suitable formation, such as groove 14, is imparted thereto. This turned over portion is, after the insertion of a closure disc 11 in groove 14, turned inwardly, as shown at the right hand side of Fig. 1, to secure the disc 11 in place. 55

The outward turning of the upper edge of the body, instead of the inward turning usual in containers of this class, avoids the apron extending downwardly inside the finished container below the end closure 11, which is considered to be undesirable when the container is used for certain classes of goods.

In Fig. 3 the end closure, instead of consisting of a flat disc as in Fig. 1, is shown as a disc 12 having a flange 13, and is securely held in its place in the container by turning over the upper edge of the latter to surround such flange, and which upper edge in this case has not necessarily been previously turned over outwardly, as when this method of closing the container is employed there is no apron depending below the closure.

When it is desired to open a container formed as above described, this is effected by tearing out the strip 6 between the weakening lines, as described in the prior applications hereinbefore referred to. This will separate the upper end of the container with the closure attached thereto, and this separated upper end can be subsequently used as a lid or cover if all the contents have not been taken out, the depending edge of the separated cover portion fitting outside the upstanding edge of the inner wall left by the removal of the strip 6, as shown in Fig. 2.

One of the advantages of the present invention

is that it will not be necessary to provide a separate cover to be used in case of need after the original closure has been removed, as the cover made integral with the container and separated as above described will serve very effectually for this purpose.

What I claim and desire to secure by patent is:—

A paper container comprising a body having a double wall composed of an inner ply and an outer ply and provided at points spaced from one end with weakening lines spaced apart and forming a strip therebetween extending from end to end of the blank and the portion of which on the outer ply is of greater width than the portion 10 thereof on the inner ply, from which said wall is formed, the first named end of the wall having a closure and being separated from the remaining portion of the wall when said strip is torn out, the body of said container being conical, said 15 separable end portion of its wall being at the larger end thereof and after tearing of said strip and re-application of the separable end portion to the body being adapted to fit on the outer surface of the inner ply of the wall left exposed by 20 the removal of such strip and thereby adapt the cover to be refitted on the body wall after the strip has been torn out and the cover has been removed.

HARRY WOOTTON.
